(57) CLAIM

The ornamental design for a headboard, as shown and described.

DESCRIPTION

FIG. 1 is a left front perspective view of a headboard showing my new design;

FIG. 2 is a side elevational view, the opposite side being a mirror image thereof; and,

FIG. 3 is a front elevational view thereof.

The views of the headboard not shown form no part of the claimed design. The dashed lines depicting cross rails, large feet, finials, and drawer rectangular ornamentation represent environmental elements only and form no part of the claimed design.

1 Claim, 3 Drawing Sheets
